UNITED STATES PATENT OFFICE.

IRWIN F. KEPLER, OF AKRON, OHIO, ASSIGNOR TO THE B. F. GOODRICH COMPANY, OF NEW YORK, N. Y., A CORPORATION OF NEW YORK.

ENDLESS BELT OR BAND.

Application filed November 8, 1921. Serial No. 513,639.

To all whom it may concern:

Be it known that I, IRWIN F. KEPLER, a citizen of the United States, residing at Akron, in the county of Summit and State 5 of Ohio, have invented a certain new and useful Endless Belt or Band, of which the following is a specification.

This invention relates to bands or endless belts and is especially applicable to power-10 transmission belts including fan belts of automobiles. Its principal object is to provide an improved, durable belt, of simple construction which may be made compara-15 tively stretchless, and yet strong and highly flexible.

Of the accompanying drawings:

Fig. 1 is a perspective view of a preferred form of my improved belt.

Fig. 2 is a fragmentary view showing the 20 weave of a preferred belt-forming ribbon.

Referring to the drawings, 10 is the belt, comprising a strip or ribbon of straight-laid, rubberized fabric, coiled upon itself in a plurality of convolutions 11, 11 vulcanized together. In the preferred embodiment of my invention here shown, the belt-forming strip or ribbon is straight woven, with selvaged edges (Fig. 2), the warp 12, 12 running lengthwise of the ribbon and the weft 13, 13 being doubled back around the outermost one of the warp threads at the edge of the ribbon. The weave here shown is of the herringbone style, each warp thread passing alternately over and under 30 two of the weft threads, and vice versa, the threads thus having a relatively small amount of crimp and consequently a small amount of stretchability as compared with the threads of ordinary fabric. The ribbon 35 being of uniform width, the selvage edges of successive convolutions directly overlie each other, forming strong wear-resisting edges for the belt, so that it is not rapidly worn or frayed at the edges if run on flanged 40 pulleys or against a belt-shifter.

Each end portion 14 of the ribbon is cut to a tapered form so that the cut edges 16 present severed ends of both the warp and weft threads, and said cut edges are of considerable length, and for the most part lie well within the side edges of the belt. The end portions 14, 14 are preferably, as shown in Fig. 1, cut to the same angle on both sides, so that their tips lie at the middle of the belt. 50 In the manufacture of the belt each tip is

overlaid with a thin piece 15 of sheet rubber which becomes united with the rubber coating of the ribbon during vulcanization and aids in binding said tip to the body of the belt.

The end portions 14 of the ribbon being cut as above described, a long, raw edge is provided, and this character of edge alone, as compared with a selvage edge, gives a superior adhesion of the strip end to the 65 body of the belt, as the rubber, during vulcanization under pressure, intimately associates itself with the fibers of the severed thread ends, the twist of the latter being relieved by the cutting, permitting them to 70 flatten somewhat against the body of the belt, and they are thus firmly anchored in place. Since a large number of weft threads are thus anchored at their ends, and the warp threads when pulled grip the weft 75 threads by reason of the crimp of the weave the anchorage of the weft-thread-ends is added to that of the warp-thread-ends, and a very good adhesion of the end of the strip or ribbon is secured, especially when, as 80 shown, the end portion is cut on both edges and given a taper of considerable length. This form of taper has the further advantage that in use on the usual pulleys the 85 line of flexure of the belt is transverse to the edges 16 of the strip-end, with always a substantial anchorage of the strip-end beyond the point of flexure except near the tip, and there the resistance to flexure represented by the stiffness of the strip-end is 90 reduced, by reason of the narrowed width of the strip-end, so that the tip is not impelled to spring away from the body of the belt.

Other advantages of the strip-end cut 95 obliquely at both sides are that there is no abrupt angle or shoulder on the strip-end at the edge of the belt to be struck or torn loose by a pulley flange, and the tip and adjacent part of the strip-end is sufficiently 100 spaced from the edges of the belt to avoid the disintegrating effect of the oil or grease which may encroach upon the belt from the sides. The straight-woven fabric makes the belt substantially non-stretchable and permits a thin and consequently highly flexible 105 belt to be produced, having ample strength.

I claim:

1. An endless belt comprising a convoluted ribbon of rubberized fabric having selvaged side edges lying at the edges of the belt and 110

an end cut on a line traversing both the warp and the weft of the fabric, said end overlying and being vulcanized under pressure to the body of the belt.

5. An endless belt comprising a convoluted ribbon of rubberized woven fabric having both side edges thereof selvaged and a woven end thereof cut to a tapered form, said tapered end overlying and being vulcanized under 10 pressure to a part of said ribbon, both side edges of said tapered end receding from the side edges of the part of said ribbon which it overlies.

15. An endless belt comprising a single spirally wound strip of straight-laid, rubberized, woven fabric having a tapered woven end, said tapered end overlying and being vulcanized under pressure to a part of said strip, both side edges of said tapered 20 end receding from the side edges of the part of the strip which it overlies.

25. An endless belt comprising a single ribbon of straight-laid, rubberized, woven fabric wound in a plurality of spiral convolutions, said ribbon having both side edges selvaged and both woven ends cut to a tapered form, the side edges of said tapered ends receding

from the side edges of the adjacent parts of the ribbon, said convolutions being secured to each other by vulcanization.

30

5. An endless belt comprising a single section of rubberized webbing wound to provide a loop having several plies and having an end thereof cut to a tapered form, said tapered end overlying a portion of the rubberized webbing and being vulcanized thereto under pressure, the side edges of the tapered end receding from the side edges of the said portion of the webbing.

35

6. An endless belt comprising a single section of rubberized webbing wound to provide a loop having several plies, said webbing having both ends cut to a tapered form, the side edges of the tapered ends receding from the side edges of portions of the webbing adjacent thereto, said tapered ends being overlaid at least in part by a thin piece of sheet rubber, the several plies including the tapered ends being secured together by vulcanization.

40

In witness whereof I have hereunto set my hand this 4th day of November, 1921.

45

IRWIN F. KEPLER.
